The Babcock & Wilcox Company, Bayonne,
N. J., a corporation of New Jersey

Application March 21, 1931, Serial No. 524,252

12 Claims. (Cl. 257—230)

This invention relates to improvements in fluid heat exchange apparatus. Specifically it presents an arrangement of helically finned tubes, as an improvement in fluid heat transfer apparatus.

An object is to render more effective and complete the heat exchange from one fluid to another.

The invention is also intended to reduce heat losses resulting from ineffective and incomplete scouring action along fluid containing tubes receiving heat from passing gases.

A further object is to promote economy of cost of installation and the compactness of fluid heat exchangers.

The invention is set forth with particular reference to the accompanying drawings, in which: Fig. 1 is a sectional view indicating a part of a return bend economizer having adjacent fluid conducting tubes formed with oppositely projecting fins, which are interlocked.

Fig. 2 is a detailed view of a section of one of the finned tubes of a heat exchange apparatus such as that shown in Fig. 1.

Fig. 3 is a detailed view of sections of adjoining finned tubes with oppositely directed interlocked fins.

Fig. 4 is a diagrammatic view with legends indicating the action of gases upon finned tubes having a pitch greater than their critical pitch.

Fig. 5 is a fragmentary view showing adjoining fluid heat exchange tubes with fins arranged as right hand and left hand helices and practically completely overlapped.

Fig. 6 is a fragmentary sectional view indicating finned sections which may be formed by making radial saw cuts in the illustrative fins.

The passage of a stream of gas transversely of a helically finned tube results in a deflection of the gas in one direction on one side of the tube, and in the opposite direction on the opposite side of the tube. The deflection of the gas is in opposite directions on opposite sides of the tubes, this action taking place according to the characteristics of the helices. Such tubes have advantages when used as parts of heat transfer apparatus but they cannot be used effectively in such apparatus without the present invention.

For the best utilization of helically finned tubes in fluid heat exchange apparatus there must be a maximum heat transfer per cubic foot of space occupied by the apparatus. This condition requires that, in an apparatus using a bank of helically finned tubes, they be overlapped.

If adjoining overlapped helically finned tubes all have their fins arranged as left hand helices, or if all of the tubes have their fins arranged as right hand helices, the tubes cannot be completely interlocked or overlapped under certain conditions. One condition pertains when the pitch is of sufficient length, and the fin is of sufficient length. In such a situation, the upward slant of one fin, and the downward slant of the other would cause the fins of adjoining tubes to contact so as to cause the fins to touch before the fin of one tube touched the adjoining tube.

A maximum interlocking of adjoining helically finned tubes is necessary to obtain the maximum amount of heat transfer surface per cubic foot of space occupied by the fluid heat exchange apparatus. To permit such a maximum of interlocking there must be a limit of pitch for a given depth of fin.

It is a part of this invention to arrange helically finned tubes in a single row, the adjacent tubes in a row having helices of alternate directions. That is to say, the first and third tubes of the row have, for example, fins arranged as right hand helices, and the second and fourth tubes have fins arranged as left hand helices.

A second consideration of the action taking place when a stream of gas encounters one of the tubes above mentioned, will now be considered. The gas passing a tube encounters a fin on both sides of the tube, at an angle to the direction of motion of the stream of gas. The fin then acts like a deflection band. The up-stream side of the fin actually deflects the gas. The gas passing on the down-stream side of the same fin or band will not change its direction to follow the fin more than a small angle. If the angle of the fin is sufficiently large, there will be a loss of contact between the fin and the gas. This loss of contact causes a part of the down-stream side of the fin to become ineffective because it is not scoured by the gas. In this situation, the heat transfer is not as complete as it is when the fin is at the proper angle. By the expression "lower side of the fin" the downstream side of the fin is meant; it is the side opposite the side causing actual deflection of a part of the fluid stream flowing across the tubes.

Referring to Fig. 4 of the drawings it will be seen that there is a legend "Short circuiting". This indicates an action taking place at the lower or downstream side of a fin arranged at an angle greater than the critical angle. In the event that action takes place as indicated in Fig. 55

4 there is a loss in efficiency due to the short circuiting. The gases have a considerable downward deflection (which is merely indicated as downward on account of the position of the elements in Fig. 4 merely for the purpose of illustration) due to the fact that the fin is shown at an angle greater than the critical angle.

It is a part of this invention to limit the helical fins to those of a pitch less than the critical 10 pitch. The critical pitch is the greatest pitch at which there is no tendency to short circuit the gas relative to the down-stream side of the fin. When the fin has a pitch equal to or less than the critical pitch, there is complete contact with 15 the gas. When the pitch of the fin is above the critical pitch there is short circuiting on the lower side of the fin. By "short circuiting" reference is made to the loss of gas and fin contact.

Corresponding to the critical pitch of the helical fin there is a corresponding critical angle for 20 the boundary face of the fin section whether that section be a part of a fin or otherwise. The fin might not be helical in form, but it must comply with the teachings of this invention. It must be inclined to the tube surface at less than the critical angle. The fins may be interrupted, in which case, they will be the equivalents of vanes. Also the fins may have plane surfaces in which case they are inclined fins. The objective always is to limit the fins so that the air or gas can 25 contact with the downstream side in spite of the inclinations of the fins.

If the fins of adjoining tubes turn in the same direction, then the gas passing between those tubes will have a part of its body deflected in one direction, and an adjoining part of the same gas stream will be deflected oppositely. For example, one part of the gas stream would be deflected downwardly and an adjoining part of the same stream deflected upwardly under those conditions. Such action produces eddy currents, and causes loss of energy, which energy might otherwise be available for scrubbing the heat transfer surface and promoting effective heat transfer. 35 In the illustrative arrangement of helically finned tubes here described, the gas stream parts between the helically finned tubes are deflected in the same direction, and loss of energy is thereby obviated. The downward and upward gas deflections mentioned take place when the tank of finned tubes extends across a gas stream flowing horizontally.

This invention is concerned with apparatus in which the flow of an external fluid past fluid 45 heat exchange tubes is such that the flow is within a range capable of economically effecting desirable results in industrial installations. This range is referred to as the "turbulent velocity range". It is such that the fluid velocities may cause such extensive eddy currents that there is a tremendous loss in rate of heat exchange due to loss of contact between the external fluid and the tubes contacted by the fluid. This is accepted terminology, in the science of aerodynamics, for fluid conditions in which it is a distinct problem to provide for complete fluid and 55 solid contact when the solids extend transversely of the direction of flow of the fluid. This range of velocities is in direct contradistinction to the fluid velocity range known as the "laminar range". When solids are disposed in the path of fluids coming within this latter range there is no problem whatever in the prevention of loss of solid and fluid contact. Whatever the angle of 60 solid to the direction of fluid flow may be, there

is complete contact between the fluid and the solid.

With the illustrative device, there is less eddy current loss of energy. There is an adequately increased proportion of flow energy used to promote heat absorption in the arrangement wherein adjoining tubes having oppositely directed helices are used.

The illustrative apparatus minimizes eddy current loss and also losses of heat due to ineffective heat transfer by the pitch limitations of the fins whereby all surfaces on both sides of the fin are effective and short circuits are eliminated.

A maximum amount of heat transfer per 15 cubic foot of space occupied by the apparatus is effected by the interlocking of the fins of adjoining tubes. This arrangement also provides a more compact apparatus and increases the effective heat transfer for a given draft loss. 20

In Fig. 1 there is shown a heat exchanger having fluid conducting tubes 10 and 12. The tubes 10 are indicated as having fins 14 in heat transfer contact therewith and formed substantially as a continuous left hand helix about the 25 tubes. The adjacent tubes 12 are shown as equipped with fins formed similarly to the fins of the tubes 10, except that the fins are generally in the nature of continuous right hand helices, with the fins arranged in interlocking 30 relationship with the fins of the adjoining tubes 10.

The fluid heat exchange apparatus shown in Fig. 1 includes return bend connections 18, connecting adjacent tubes in such manner that the 35 contained fluid flows back and forth across the gas stream, the direction of which is indicated by the arrow 20. Preferably the finned sections of the tubes are mounted in a casing indicated by the walls 22 and 24. Between these walls there 40 is confined a fluid current.

Securing the fins to the tube by arc, flame, pressure or resistance welding brings about good heat transfer relations between the tube and the fins. Under certain conditions the fins may be brazed or 45 soldered to the tubes.

In Fig. 2, a section of the illustrative tube is shown cut away longitudinally through the tube and through the fins. There are lines of weld metal 26 indicated in this figure. The cross section relationships of the bases of the fins and weld metal is indicated by the upper part of Fig. 2, wherein deposits 28 and 30 of weld metal are shown as constituting a broad heat transfer base 50 uniting the fin to the tube. 55

In Fig. 1, the return bends 18 are shown as provided with flanges 32, preferably held in fluid tight contact with the flanges 34 on the fluid conducting tubes.

While this invention has been described with 60 reference to particular constructions it is to be understood that the invention is not limited thereto, but that it is of a scope commensurate with the scope of the appended claims.

What is claimed is:

1. Fluid heat exchange apparatus comprising, in combination, a row of parallel tubes conveying one fluid, means for causing a second fluid to move across the row of tubes, and helically arranged external fins on each tube making thermal 70 contact therewith, there being alternate right hand and left hand fins on successive tubes along the row.

2. Fluid heat exchange apparatus comprising, in combination, a row of parallel tubes conveying 75

- one fluid, means for causing a second fluid to move across the row of tubes, and helically arranged fins of less than the critical pitch on each tube, each fin making thermal contact with its tube, there being alternate right hand and left hand fins on successive tubes along the row. 5
3. In fluid heat exchange apparatus, a bank of parallel tubes through which one fluid moves, means for causing a second fluid to flow across 10 the tubes of the bank, and helical fins in thermal contact with the tubes and alternately arranged on successive tubes as right and left hand helices, the fins and the tube being completely overlapped or interlocked so that the fins on one tube are in 15 contact with an adjoining tube.
4. In fluid heat exchange apparatus, a bank of parallel tubes through which one fluid moves, means for causing a second fluid to flow across the bank of tubes, and helical fins in thermal 20 contact with the tubes, and alternately arranged on successive tubes as right and left hand helices, the fins on adjoining tubes being interlocked. 25
5. Fluid heat exchange apparatus comprising, in combination, a row of parallel tubes conveying one fluid, means for causing a second fluid to move across the row of tubes, and helically arranged fins electrically welded on each tube and making thermal contact therewith, there being alternate right hand and left hand fins on successive tubes along the row. 30
6. In fluid heat exchange apparatus, parallel tubes each having helical fins, the fins on adjoining tubes overlapping and being formed respectively as right and left hand helices.
7. In fluid heat exchange apparatus, parallel tubes each having helically extending fins, the fins on adjoining tubes overlapping and being formed respectively as right and left hand helices. 5
8. In fluid heat exchange apparatus, parallel tubes each having a helical fin, the fins on adjoining tubes overlapping and being formed respectively as right and left hand helices. 10
9. In fluid heat exchange apparatus, a bank of tubes conducting a fluid, and helically arranged fins in thermal contact with the tubes, the fins on adjacent tubes being arranged respectively as right and left hand helices. 15
10. In fluid heat exchange apparatus, a plurality of tubes conducting a fluid, and helically arranged fins secured on the tubes in thermal contact therewith, the fins on adjacent tubes being interlocked and arranged respectively as right and left hand helices. 20
11. In fluid heat exchange apparatus, a plurality of tubes conducting a fluid, and helically arranged fins of less than critical pitch in thermal contact with the tubes, the fins on alternating tubes being arranged respectively as right and left hand helices. 25
12. In fluid heat exchange apparatus, a plurality of tubes conducting a fluid, and helically arranged fins of less than critical pitch in thermal contact with the tubes, the fins on alternating tubes interlocking and arranged as right and left hand helices. 30
